ROCK DRILLING APPARATUS

Göte Ragnvald Lindberg, Saltsjöbaden, Sweden, assignor to Atlas Copco Aktiebolag, Nacka, Sweden, a corporation of Sweden

Filed Oct. 3, 1961, Ser. No. 142,618

14 Claims. (Cl. 173—43)

This invention relates to a drilling apparatus and more specifically to a mobile drilling apparatus intended for underground drilling operations. A primary object of the invention is to provide a novel and efficient mobile drilling apparatus especially suited for mechanized rapid drilling of groups of drill holes transversely of the direction of a drift or crosscut, for example during application of sub-level caving. Another object of the invention is to provide a mobile drilling apparatus capable of drilling groups of parallel drill holes as well as groups of holes in fan-shaped arrangement in upward and downward direction transversely of the drift. A further object of the invention is to provide a mobile drilling apparatus capable of drilling groups of drill holes transversely of the drift and efficiently operable in comparatively small drifts. A still further object of the invention is to provide a mobile drilling apparatus capable of drilling groups of drill holes in comparatively small drifts in a fan-shaped arrangement covering a wide angle transversely of the drift from one side of the floor to the other.

In the accompanying drawings one preferred embodiment of a rock drilling apparatus according to the invention is illustrated by way of example which embodiment, however, is by no means limiting for the scope of the invention which may be modified in several different ways within the scope of the appended claims.

FIG. 1 is a side view of a drilling apparatus according to the invention with the drill and feed bar in the longitudinal central plane of the drilling apparatus.

FIG. 2 shows a longitudinal fragmental section of a drift and indicates diagrammatically the maximum backward and forward tilt of the apparatus in FIG. 1 when positioned in said drift.

FIG. 3 shows a transverse section of a drift and indicates diagrammatically a group of drill holes, positioned by the apparatus in FIG. 1 in upward fan-shaped arrangement with the fan center in the middle of the drift.

FIG. 4 indicates diagrammatically and in correspondence with FIG. 3 a group of drill holes in downward fan-shaped arrangement.

FIG. 5 is a back view of the apparatus in FIG. 1 with the drill and feed bar shifted to the left of the longitudinal central plane of the drilling apparatus.

FIG. 6 is a view on line 6—6 in FIG. 1.

FIG. 7 shows a transverse section of a drift and indicates diagrammatically a group of drill holes positioned by the drilling apparatus in double fan-shaped arrangement with the fan centers at opposed corners of the drift.

FIG. 8 shows a transverse section of a drift and indicates diagrammatically a group of parallel upward drill holes positioned by the drilling apparatus.

FIG. 9 is a back view of the apparatus in FIG. 1 with the operating panel removed and with the drill and feed bar shifted to the right of the longitudinal central plane of the apparatus.

FIG. 10 is an enlarged view on line 10—10 in FIG. 1.

FIG. 11 is an enlarged view of the upstanding structure and the boom system of the drilling apparatus when positioned according to FIG. 5.

FIG. 12 is an enlarged view on line 12—12 in FIG. 1, and

FIG. 13 is a view on line 13—13 in FIG. 11.

The drilling apparatus for underground drilling operations consists of a mobile substructure or carriage 21 hav-

ing two pair of wheels 22 which may be arranged to ride upon a trackway 23 extending the length of drift to be worked or may be tired or crawler-tracked resting directly against the floor of the drift. The carriage 21 has a forward frame portion 24, FIG. 6, a narrow middle portion 25, and a back portion 26. Mounted on the carriage 21 near the back portion 26 is a stand 27 for an operating panel. Pivotedly mounted by means of transverse pivots 29 on opposed bearings 28 carried by the forward frame portion 24 is an upright main supporting structure 30, the upper part of which forms an elongated pillar 31. Inside of and along the upstanding supporting structure there extends a jack mechanism 32, for example a power cylinder, the piston rod of which protrudes axially out of the pillar 31 and forms a pointer bar 33, engageable with an extraneous abutment such as the roof of the drift by extension of the jack mechanism.

To the sides of the forward frame portion 24 there are fixed brackets 34 carrying vertical power jacks 35, the piston rods of which are intended to contact the floor of the drift for supporting purposes, the pointer bar 33 simultaneously contacting the roof thereby firmly fixing the upstanding structure 30 with respect to the drift. A double acting power cylinder 36 is pivotally connected to the upstanding structure 30 near its middle portion at a pivot 37 while its opposed end is pivotally fixed to the forward frame portion 24 by means of a pivot 38. By extending and contracting the power cylinder 36 the upstanding structure 30 together with its associated parts may be tilted to various working positions between the backwardly tilted position 39 indicated in FIG. 2 and a forward position 40 the latter also suitable for transportation of the drilling apparatus.

Slidably arranged between an upper and lower position on the pillar 31 is a bracket 41 carrying thereon two parallel laterally spaced-apart pivots 42 and 43, the pivot 42 lying in the central longitudinal plane of the carriage 21 and upstanding structure 30. Pivotally arranged on the pivot 42 for swinging movement in a transverse vertical plane with respect to the carriage 21 is a boom 44. At the opposite end of the boom 44 is provided a bearing bushing 45 which, with its associated elements as described below, provides for the support of the feed bar or beam channel 53, the drill, and associated parts. Centrally on the boom 44 is arranged a pivot 46, FIG. 10, pivotally connected to the boom 44 and fixed to one end of a link 47, the other end of which is swingably connected to a pivot 48 on the lower portion of the upstanding structure or support means 30 vertically below the pivot 42 of the slideable bracket 41. The end of the link 47 adjacent the pivot 46 is extended in sidewise direction and is pivotally connected at 49 to one end of a double acting power cylinder 50. The opposite end of the power cylinder 50 is connected to the upstanding structure 30 at 51 adjacent one of its transverse pivots 29. By contracting and extending the power cylinder 50, the link 47 may be swung from one side of the central plane of the drilling apparatus to the other, whereby the end of the boom 44 adjacent the pivot 42 is raised and lowered together with the slideable bracket 41 while the other end of the boom 44 carrying the bushing 45 swings from one side of the carriage to the other to position the rock drilling apparatus in any of the plurality of horizontal positions between the two extremes of travel of boom 44 from one side of the carriage to the other, all of which positions are substantially within a vertical plane transversely of the carriage, which vertical plane may be tilted through a plurality of positions by the action of cylinder 36 acting to tilt supporting structure 30 around pivots 29.

A trunnion or pivot means 52 is pivotally carried by the bearing bushing 45 of the boom, which trunnion 52 extends transversely to and is fixedly attached to one

end of an elongated guide member 53. Adjacent the trunnion 52 the guide member is provided with a cross arm 54 protruding transversely with respect to the trunnion 52 and the guide frame 53 and carrying a pivot 55 at its free end. Between this pivot 55 and the pivot 43 on the slideable bracket 41 there is coupled a double acting power cylinder 56. By extending and contracting the power cylinder 56 the cross arm 54 may be swung substantially from the full line to the dotted line position of FIG. 11 and vice versa which means a corresponding swinging of the guide member 53 and associated parts, all substantially in vertical or tilted transverse planes. In the state of extension of the power cylinder 56 illustrated in FIGS. 5, 9, 11 the power cylinder 56 forms part of an elongated parallelogram linkage the other link members of which are constituted by the boom 44, the cross arm 54, and the slideable bracket 41.

The guide member 53 is provided with elongated spaced-apart guides 57 for slideable accommodation of a saddle 158 carrying an elongated feed bar 58. A double acting power cylinder 59 is connected to a pivot 60 on the saddle 158 and to a pivot 61 on the guide member 53 and serves to move the saddle 158 together with the feed bar 58 longitudinally of itself relatively to said guide member 53 and said trunnion 52 for compensating differences in the distance between the trunnion 52 and the rock face in connection with changes of the angular position of the feed bar 58. 62 indicates a drill feed motor which for example by a feed screw 63 or by other means serves to feed a drill 64 together with a drill steel 65 towards a rock face. The drill 64 is guided for reciprocation by spaced-apart guide grooves 66 provided on the feed bar 58, which also carries a conventional drill steel guide 67. The arrangement of the feed bar 58 together with its associated parts is preferably such, that it may be reversed on the saddle 158 with respect to the guide member 53, e.g. may be disconnected from the saddle 158 and reinserted on said saddle with the drill pointing in the opposite direction.

The pressure fluid for operation of the different jacks, power cylinders, the feed motor, and the drill of the illustrated drilling apparatus is supplied from suitable sources not illustrated, and the various hoses for conveying pressure fluid have been omitted since they would make the drawing rather congested and since the provision of such hoses is obvious to those skilled in the art.

In FIG. 1 the drilling apparatus is illustrated in position for drilling vertical holes in upward direction with the guide member 53 and feed bar 58 in the longitudinal central plane of the drilling apparatus and the drift. After choosing a suitable tilt of the apparatus by means of the power cylinder 36 and extension of the pointer bar 33 against the roof and the power jacks 35 against the floor the apparatus is ready for operation. It is obvious that swinging of the cross arm 54 upward or downward in FIG. 1 by means of the power cylinder 56 moves the guide member 53, the feed bar 58 and the drill 64 in fan-shape around the trunnion 52. This enables the operator to drill a group of holes 68, FIG. 3, in upward fan-shaped arrangement transversely of the drift with the fan center in the middle of the drift. The operator can do this by simply manipulating the power cylinder 56 and raising or lowering the feed bar 58 by means of the power cylinder 59.

After reversing the feed bar 58 together with the drill 64 to point in downward direction, the operator obviously in an analogous manner is able to drill holes 69, FIG. 4, in downward fan-shaped arrangement. Positioning of a drill hole downwardly in the central plane of the drift is of course prevented by the middle frame portion 24, but owing to the narrowness thereof the obstructed area will be small. As readily seen from FIGS. 3 and 4 the angle through which the fan of drill holes may be positioned is decided by the length of the feed bar 58 in its retracted position on the guide member

53. Obviously the cross section of the drift in FIGS. 3 and 4 is too small should there be a desire to use a wider fan angle. By means of the boom arrangement according to the invention, however, it is possible to extend said angle without altering the cross section of the drift. To this end the operator manipulates the power cylinder 56 and thereby places the guide member 53 together with the feed bar 58 and the drill 64 in vertically upward position corresponding to FIG. 1. By extending the power cylinder 50 the operator now throws the link 47 to the left, FIG. 5, as viewed from the operating panel. By the turning movement of the link 47 the slideable bracket 41 is brought in its downward position sliding down along the pillar 31 simultaneously with the boom 44 being swung to the left together with the trunnion 52 of the guide member 53. Owing to the parallel linkage formed by the bracket 41, the power cylinder 56, the cross arm 54, and the boom 44, the guide member 53 during such swing to the left remains in vertically upward position. By now manipulating the power cylinder 56 the operator is able to position a group of drill holes 70 in fan-shaped arrangement with the fan center at the left corner of the drift thereby covering the roof and the wall of the drift opposite to said corner. Thereupon the operator, after having brought the drill and guide frame 53 into vertical position by manipulation of the power cylinder 56, may contract the power cylinder 50 thereby swinging the link 47 from the left side of the carriage 21 over to its right side into the position of FIG. 9. Obviously the above mentioned parallel linkage keeps the guide frame 53 in the vertical position during this swing. By further manipulation of the power cylinder 56 the operator may now position a group of drill holes 71 in fan-shaped arrangement with the fan center at the right hand corner of the drift, covering by the fan angle the roof and the opposed wall of the drift. As a result, the small drift illustrated in FIG. 7 may receive drill holes in a transverse direction arranged in double fan-shaped arrangement through a wide angle completely covering the roof and the walls of the drift.

Obviously the parallel displacement of the guide member 53, the feed bar 58, and the drill 64 may be used for positioning parallel, vertical holes 72 in upward direction as indicated in FIG. 8. Of course parallel holes may be drilled also in downward direction after reversing the feed bar 58 and the drill 64 on the saddle 158 and the guide member 53 to point downwards.

The drilling apparatus above described and illustrated in the drawings should only be considered as an example and the invention may be modified in several different ways within the scope of the following claims.

What I claim is:

1. In mobile rock drilling apparatus of the character described having a mobile carriage with means mounted thereon for supporting and feeding a rock drill in a plurality of horizontal and vertical and angular drilling positions all of which lie substantially in a plane extending transversely of said carriage, the combination which comprises an elongated feed bar for carrying a rock drill and having feeding means thereon for feeding and retracting a rock drill disposed and supported thereon along said feed bar, main support means on said carriage, boom means for carrying and moving said feed bar and a rock drill supported thereon into said plurality of positions transverse to said carriage, substantially horizontal pivot means with the axis thereof substantially parallel to said carriage for interconnecting one end of said feed bar with one end of said boom means, means for movably connecting the other end of said boom means to said main support for swinging movement with respect thereto through said plurality of positions in said transverse plane, first power means on said carriage and engaging said boom means for swinging movement thereof and said pivot means with respect to said main support means to said plurality of said positions in said transverse

plane, said pivot means interconnecting said feed bar with said boom means also including means for swinging said feed bar to a plurality of angular positions about the axis of said pivot means independently of said swinging movement of said boom means, and second power means on said carriage and connected to said feed bar for the swinging thereof about said axis and operable independently of said first power means.

2. In mobile rock drilling apparatus of the character described having a mobile carriage with means mounted thereon for supporting and feeding a rock drill in a plurality of horizontal and vertical and angular drilling positions substantially all of which lie substantially in a plane extending transversely of said carriage, the combination which comprises an elongated feed bar for carrying a rock drill and having feeding means thereon for feeding and retracting a rock drill disposed thereon along said feed bar, main support means on said carriage disposed in a generally upright position and extending for a substantial distance above said carriage, boom means for carrying and moving said feed bar and a rock drill supported thereon into said plurality of positions transverse to said carriage, substantially horizontal pivot means interconnecting one end of said feed bar with one end of said boom means, the axis of said pivot means being generally perpendicular to both said elongated feed bar and said plane transversely of said carriage, means for movably connecting the other end of said boom means to said main support means for both vertical and pivotal movement with respect thereto through said plurality of positions in said transverse plane, a linkage pivotally connected between said main support means and said boom means, first power means on said carriage and engaging said linkage for imparting said pivotal movement to said boom means through said linkage, said pivot means interconnecting said feed bar with said boom means also including means for swinging said feed bar to a plurality of angular positions about said axis of said pivot means independently of said swinging movement of said boom means, and second power means on said carriage and connected to said feed bar for thus swinging said feed bar with respect to said boom means about said axis and operable independently of said first power means.

3. Rock drilling apparatus as recited in claim 2 in which said main support means comprises an upright pillar on said carriage, and said means for movably connecting said boom means thereto includes a bracket vertically slidable along said pillar with means for pivotally connecting said boom means to said bracket.

4. Rock drilling apparatus as recited in claim 2 in which said means for swinging said feed bar with respect to said boom means and about the axis of said pivot means includes a crank arm pivotally linked to said main support means forming a parallelogram linkage therewith.

5. In mobile rock drilling apparatus of the character described having a mobile carriage with means mounted thereon for supporting and feeding a rock drill in a plurality of horizontal and vertical and angular drilling positions substantially all of which lie substantially in a plane extending transversely of said carriage, the combination which comprises an elongated feed bar for carrying and supporting a rock drill and having feeding means thereon for feeding and retracting a rock drill thereon along said feed bar, main support means on said carriage disposed in a generally upright position and extending for a substantial distance above said carriage, parallelogram boom means for carrying and moving said feed bar into said plurality of positions transverse to said carriage, pivot means interconnecting one end of said feed bar with one end of said boom means and including a cross arm forming one end of said parallelogram boom means, the axis of said pivot means being generally perpendicular to both said elongated feed bar and said plane transversely of said carriage, means for movably connecting the other

end of said parallelogram boom means to said main support means for both vertical and pivotal movement with respect thereto for swinging movement thereof with respect to said main support means through said transverse plane swinging said boom means and said feed bar thereon to said plurality of said positions transverse of said carriage, a linkage pivotally connected between said main support means and said boom means for imparting said swinging movement thereto, a fluid-operated cylinder in driving engagement with said linkage for moving said boom means therethrough, said cross arm also effecting pivoting of said feed bar about the axis of said pivot means therefor for swinging thereof to a plurality of angular positions about said axis and with respect to said boom means and independently of said swinging movement of said boom means, and second power means on said carriage and connected to said cross arm for imparting said swinging movement to said feed bar.

6. Rock drilling apparatus as recited in claim 2 in which said feed bar for carrying and supporting a rock drill includes means for moving a rock drill along said feed bar in both feeding and retracting directions substantially independently of the horizontal or angular positioning of said feed bar about the axis of said pivot means, and also includes additional power means on said feed bar for imparting to a rock drill disposed thereon said movement along said feed bar.

7. In an arrangement for supporting reciprocally fed rock drilling apparatus on a mobile carriage therefor and in a plurality of horizontal and angular positions substantially all of which lie substantially in a plane generally transverse of said carriage and at an angle to the horizontal axes thereof, the combination which comprises main support means on said carriage, translating means for carrying said rock drilling apparatus on said main support means for translating movement to said plurality of horizontal positions from one side of said carriage to the opposite side thereof and in said plane thereacross, first power means on said carriage and in driving engagement with said translating means for effecting said movement and positioning thereof, substantially horizontal pivotal mounting means between one end of said rock drilling apparatus and said translating means with the axis thereof parallel to said carriage axis for providing swinging and pivoting movement of said rock drilling apparatus with respect to said translating means and about an axis substantially perpendicular to both said rock drilling apparatus and said transverse plane in each of said plurality of said horizontal positions into which rock drilling apparatus is translated by said translating means, second power means in driving engagement with said rock drilling apparatus and said pivotal mounting means therefor for thus pivoting and swinging said rock drilling apparatus independently of the operation and positioning of said translating means and said first power means therefor, and third power means on said carriage and in driving engagement with said translating means for effecting tilting movement of said translating means longitudinally of said carriage to define the angle of said transverse plane with the vertical.

8. Rock drilling apparatus as recited in claim 1 which also includes pivot means between said carriage and said main support means and means for tilting said main support means independently of the operation of all said other aforementioned means for defining the angle of said transverse plane with the vertical.

9. Rock drilling apparatus as recited in claim 2 which also includes transverse pivot means between said carriage and said main support means, and third power means on said carriage and in driving engagement with said main support means for effecting longitudinal tilting movement thereof to define the angle of said transverse plane with the vertical.

10. Rock drilling apparatus as recited in claim 5 in which also includes transverse pivot means between said

carriage and said main support means, and third power means on said carriage and in driving engagement with said main support means for effecting longitudinal tilting movement thereof to define the angle of said transverse plane with the vertical.

11. In mobile rock drilling apparatus of the character described having a mobile carriage with means mounted thereon for supporting and feeding a rock drill in a plurality of horizontal and vertical and angular drilling positions substantially all of which lie substantially in a plane extending transversely of said carriage, the combination which comprises an elongated feed bar for carrying said rock drill and having feeding means thereon for feeding and retracting said rock drill along said feed bar, main support means on said carriage disposed in a generally upright position and extending for a substantial distance above said carriage, boom means for carrying and moving said feed bar and said rock drill supported thereon into said plurality of horizontal positions, pivot means interconnecting one end of said feed bar with one end of 15 said boom means, the axis of said pivot means being generally perpendicular to both of said elongated feed bar and said plane transversely of said carriage, means for movably connecting the other end of said boom means to said main support means for both vertical and 20 pivotal movement with respect thereto through said transverse plane, a linkage pivotally connected between said main support means and said boom means, first power means on said carriage and engaging said linkage for imparting said pivotal movement to said boom means 25 through said linkage, said pivot means interconnecting said feed bar with said boom means also including a crank arm pivotally linked to said main support means forming a parallelogram linkage therewith for swinging said feed bar to a plurality of angular positions about said axis 30 of said pivot means independently of said swinging movement of said boom means, and second power means including a power cylinder connected to said crank arm in said parallelogram linkage for pivoting movement of 35 said crank arm and said feed bar about the axis of said pivot means therefor in each position of said boom means and independently of the movement and positioning thereof.

12. In mobile rock drilling apparatus of the character described having a mobile carriage with means mounted thereon for supporting and feeding a rock drill in a plurality of horizontal and vertical and angular drilling positions substantially all of which lie substantially in a plane extending transversely of said carriage, the combination which comprises an elongated feed bar for carrying said rock drill and having feeding means thereon for feeding and retracting said rock drill along said feed bar, main support means on said carriage disposed in a generally upright position and extending for a substantial distance above said carriage, parallelogram boom means for carrying and moving said feed bar into said plurality of horizontal positions, pivot means interconnecting one end of said feed bar with one end of said boom means and including a cross arm forming one end of said parallelogram boom means, the axis of said pivot means being generally perpendicular to both of said elongated feed bar and said plane transversely of said carriage, means for movably connecting the other end of said parallelogram boom means to said main support means for both vertical and pivotal movement with respect thereto for swinging movement thereof with respect to said main support means through said transverse plane swinging

said boom means and said feed bar thereon to said plurality of said horizontal positions, a linkage pivotally connected between said main support means and said boom means for imparting said swinging movement thereto, a fluid-operated cylinder in driving engagement with said linkage for moving said boom means therethrough, said cross arm also effecting pivoting of said feed bar about the axis of said pivot means therefor for swinging thereof to a plurality of angular positions about said axis and with respect to said boom means and independently of said swinging movement of said boom means, and a fluid-operated cylinder connected between said cross arm and said main support means and forming one side of said parallelogram boom means for imparting said swinging movement to said feed bar.

13. In apparatus of the character described for supporting reciprocably fed rock drills in a plurality of angular positions constituting a fan-shaped pattern transversely of the support therefor for the purpose of drilling a fan-shaped series of holes transversely of mining drifts underground and having an elongated base therefor with a substantially upright main support disposed thereon, the combination which comprises translating means disposed on said main support for carrying said apparatus on said support for translating movement thereof in a plane transverse of said apparatus from one side of said base to the opposite side thereof, substantially horizontal pivotal mounting means disposed on said translating means on the end thereof opposite from an end on said main support with the axis thereof being parallel to the longitudinal axis of said base and providing the fan-shaped drilling center, elongated feeding means with one end thereof disposed on said pivot means for carrying and supporting a rock drill therealong, first power means on said main support and in driving engagement with said translating means for movement thereof with said fan-shaped drilling center pivotal mounting means and said feeding means disposed thereon in said plane from one side of said apparatus to the opposite side thereof while maintaining the axis of said pivotal mounting means perpendicular to said transverse plane, and second power means disposed on said main support and in driving engagement with said feeding means for swinging said feeding means on said pivot means in a plurality of positions around the axis thereof and independently of said translating means.

14. Rock drilling apparatus as recited in claim 13 in which said elongated feeding means for carrying and supporting a rock drill includes an elongated feed bar for carrying said rock drill, means for feeding said rock drill along said bar, an elongated guide member extending along said feed bar, and connected to said pivot means, and means for reciprocal movement of said feed bar and rock drill with respect to said guide member.
